UNITED STATES PATENT OFFICE.

VOLNEY T. MILLER, OF KANSAS CITY, MISSOURI, ASSIGNOR TO ROBERT S. SPAHR,
OF KANSAS CITY, MISSOURI.

RAZOR-BLADE-SHARPENING MACHINE.

Application filed May 29, 1922. Serial No. 564,493.

To all whom it may concern:

Be it known that I, VOLNEY T. MILLER, a citizen of the United States, residing at Kansas City, in the county of Jackson and 5 State of Missouri, have invented a certain new and useful Improvement in Razor-Blade-Sharpening Machines, of which the following is a specification.

My invention relates to improvements in 10 razor blade sharpening machines.

One of the objects of my invention is to provide a novel machine which is simple, cheaply manufactured, durable, not liable to get out of order, which will automatically 15 feed the blades through and discharge them from the machine after they have been sharpened, and in which the progressive movement of the blades through the machine will cease, when the feeding of the blades 20 into the machine is stopped, and in which the blade in passing through the machine will first be honed and then stropped automatically.

My invention provides further novel 25 means for honing and stropping the blades.

My invention provides still further novel means by which the blades may be automatically honed and stropped at opposite sides thereof.

30 My invention provides still further novel means for feeding the blades through the machine during the sharpening operation.

My invention provides still further a 35 novel blade holder and novel means for supporting the blade holder in the machine in a manner such that the holder will accommodate itself to inequalities in the honing and stropping members.

The novel features of my invention are 40 hereinafter fully described and claimed.

In the accompanying drawings, which illustrate the preferred embodiment of my invention,

Fig. 1 is a front elevation of my improved razor blade sharpening machine.

Fig. 2 is a top view of the same.

Fig. 3 is an enlarged vertical sectional view on the line 3—3 of Fig. 6.

Fig. 4 is a cross section on the line 4—4 50 of Fig. 6.

Fig. 5 is a vertical sectional view on the line 5—5 of Fig. 1.

Fig. 6 is a vertical sectional view on the line 6—6 of Fig. 2.

Fig. 7 is an enlarged fragmental vertical 55 sectional view of a portion of the blade holder feeding mechanism and parts connected therewith.

Fig. 8 is a perspective view of one of the 60 feeding slugs.

Fig. 9 is an enlarged vertical sectional view on the line 9—9 of Fig. 6.

Fig. 10 is an enlarged side elevation of 65 one of the blade holders and a blade mounted therein.

Fig. 11 is an enlarged horizontal section on the line 11—11 of Fig. 6.

Fig. 12 is a horizontal section enlarged 70 on the line 12—12 of Fig. 6, some of the parts being omitted, and showing the oscillating blade holder guide section in one position.

Fig. 13 is a view similar to Fig. 12, the 75 oscillating guide section being shown in another position.

Fig. 14 is an enlarged vertical section on the line 14—14 of Fig. 6.

Fig. 15 is a longitudinal horizontal sectional view of a portion of the channel guide 80 and the lower end of a blade holder mounted therein.

Fig. 16 is an enlarged horizontal sectional view on the line 16—16 of Fig. 6.

Fig. 17 is a fragmental vertical sectional view, enlarged, on the line 17—17 of Fig. 10. 85

Similar reference characters designate similar parts in the different views.

1 designates a suitable supporting frame on which is mounted on vertical bearings 2, Figs. 1, 5 and 6, a longitudinal blade supporting guide, comprising a horizontal tube 3, slotted its full length in its upper side, and which is disposed between and parallel with the adjacent flat sides of two abrading members comprising preferably two wheels 4, secured to and rotatable with a horizontal transverse shaft 5, which is rotatable in standards 6, supported by the frame 1. The wheels 4 are spaced apart by a sleeve 7.

Each wheel 4 is provided on its inner side 100 with a central circular recess 8, Fig. 5, in which is mounted an abrading disk 9, having an inner flat side and having its outer side bearing against a plate 10, against the outer side of which bear set screws 11, by which the honing disk 9 may be inwardly and outwardly adjustable. The shaft 5 has two threaded portions on which are respec-

tively fitted two nuts 12, which respectively bear against the outer ends of the hubs of the wheels 4. By adjustment of the nuts 12, the wheels 4 may be adjusted longitudinally 5 on the shaft 5, with reference to the supporting guide 3.

Secured to and rotatable with the shaft 5, Figs. 1, 2 and 5, is a pulley wheel 13, which has mounted on it a belt 14, which is mounted 10 on a pulley wheel 15, which is secured to a larger pulley wheel 16 rotatably mounted on a horizontal stud 17 supported by the frame 1. On the pulley wheel 16 is mounted 15 a belt 18, which is mounted on a pulley 19, secured to the armature shaft 20, of an electric motor 21. By means of the gearing described, the motor 21 drives the shaft 5. One end of the latter may have secured to it 20 an abrading wheel 22, which may be used for sharpening knives, scissors or other articles.

The inner side of each abrading wheel 4 has a concentric abrading surface comprising preferably an annular sheet of leather 23, the inner side of which is employed for stropping the razor blades and the inner surface of which is flush with the inner flat side of the honing disk 9.

Used in connection with the mechanism 30 just described are razor blade holders, each of which consists of a vertical substantially flat body 24, see Figs. 1, 6, 7, 9, 10 and 17, the lower end of which has the form of two conic frusta disposed base to base with 35 their axes horizontal. This enlarged lower portion of the blade holder body is designated by 25, and is adapted to be slidably mounted and adapted for travel in the supporting guide 3, and to oscillate therein in 40 all directions.

Each body 24 has at its upper end a fixed jaw 26, adapted to co-operate to clamp a razor blade 27 with a movable jaw 28, which is pivoted on a transverse screw 29 so as to be swung thereon toward and from the jaw 26. For effecting such swinging, there is provided a vertically slidable wedge plate 30, having a vertical slot 31, through which extends a screw 32, mounted in the body 24. By sliding the plate 30 upwardly, the jaw 28 may be swung so as to clamp a blade 27 against the jaw 26, after which the screw 32 may be tightened to hold the wedge plate 30 in the clamping position.

The blade holders are arranged to be fed consecutively forwardly through the guiding tube 3, by the following described mechanism.

Slidably mounted on the frame 1 below 60 the guiding support 3 is a pawl carrying member 33, Figs. 5, 6, 7 and 14, which has pivotally mounted on its lower ends on a transverse pin 34 a pawl 35, having two downwardly spaced apart projections 36 and 65 37, adapted to be alternately engaged by a

block 38 secured to the upper side of a reciprocative plate 39 slidably mounted in suitable guides in the frame 1 and reciprocative below and parallel with the guiding 70 supporting tube 3.

For reciprocating the plate 39, it has secured to it at its under side the upper ends of the arms of a U-shaped vertical guiding member 40 in which is mounted a roller 41, which is adapted for vertical travel between 75 the arms of the member 40, and which is rotatably mounted on a transverse pin 42, fixed in a crank 42', which is secured to a horizontal shaft 44, rotatable in a bracket 45, which is supported by the frame 1. A 80 pulley wheel 43 is rigidly secured to the shaft 44.

A belt 46, Fig. 1, connects the pulley wheel 43 with a smaller pulley wheel 47 which is secured to and rotatable with the 85 pulley wheel 16.

When the latter is rotated by the motor 21, the belt 46 will rotate the wheel 43, and the roller 41, by means of the roller guiding member 40 will reciprocate the plate 39 90 and the block 38 once during every revolution of the wheel 43.

When the block 38 moves to the right from the position shown in Fig. 6, the block 38 will engage the projection 36 of the pawl 95 35 and by means of the pawl will force the member 33 to the right to the position shown in dotted lines in Fig. 6, when the roller 41 has reached the position shown in dotted lines in said figure.

Pivoted in the upper end of the member 33 on a transverse pin 48, Figs. 6 and 7, is a pawl 49, which is adapted for travel in a longitudinal slot 50, provided in the bottom of the guiding tube 3, Figs. 6 and 7. 100 When the pawl 49 is in the position shown in dotted lines in Fig. 6, it is adapted to engage the rear end of the portion 25, of a blade holder which has been inserted in the supporting tube 3, as shown at the right in Fig. 6. Upon the forward movement of the block 33, due to the block 38, engaging the projection 37 of the pawl 35, the blade holder thus engaged will be fed forwardly to the predetermined position occupied by 110 the second blade holder at the right in Fig. 6, at which time the forward end of the pawl 35 will engage a transverse pin 51, Fig. 6, which has its ends respectively mounted in any pair of transverse holes 52, provided in 115 two parallel plates 53, supported by the frame 1, parallel with the tube 3 and each of which on its inner side has a longitudinal groove 54 in which the plate 39 is slidably fitted.

The preceding blade holders will be fed forwardly from said pre-determined position by the succeeding blade holders, which are consecutively fed forwardly to the pre-determined position by the pawl 49, as the 120 125

succeeding blade holders are successively placed in the tube 3. This pre-determined position may be varied by placing the removable pin 51 in different pairs of holes

52. In the event that it is not desired to place any more blade holders in the tube 3, those that have been fed to the pre-determined position may be fed forwardly through and discharged from the tube 3 at

10 the left end thereof, as viewed in Fig. 6, by placing successively in the tube 3 slugs 55, one of which is shown in Fig. 8, and each of which corresponds in length, form and size to the lower end portion 25 of a blade holder.

15 The forward end and lower edge of the pawl 35 is beveled and is the part of the pawl which engages the lifting pin 51.

For limiting the downward swinging of the pawl 35, there is mounted in the member 33 a transverse pin 56, Figs. 6, 7 and 14.

20 After the blade holders have crossed in their forward travel a vertical diametrical plane through the axes of the wheels 4, and perpendicular to the tube 3, the blade holders are laterally oscillated, so that the upper edges of the blades 27 will first be brought alternately into contact with the flat inner sides of the honing disks 9, and, later, as the holders are fed forwardly, the blades 30 will alternately be brought into contact with the stropping sheets 23. Thus, each blade in traveling through the machine will first be honed and then stropped by the members 9 and 23 respectively.

35 For supporting the blade holders vertically out of contact with the abrading surfaces before the blade holders reach the honing position, there are provided two guiding bars 57 disposed parallel with and 40 at opposite sides of the tube 3 and which are supported by posts 58 supported vertically on the frame 1.

45 For supporting the blade holders vertically, after the stropping operation and before they have been discharged from the tube 3, there are respectively mounted on two vertical posts 59, supported by the frame 1, two horizontal guiding plates 60, and 61 having parallel forward portions and which 50 diverge from each other at their rear ends, see Figs. 1, 2, 6, 12 and 13.

55 For oscillating the blade holders so that the blades 27 shall contact alternately with the flat abrading sides of the wheels 4, after the holders have crossed the vertical plane of the axes of the abrading wheels, there is secured to the upper side of the reciprocative plate 39 a channel guiding member 62, which is pivoted on a vertical pin 63 mounted in the plate 39, and which is adapted to be swung to different positions oblique to the line of travel of the plate 39, and which is adapted to be secured in the position to which it may be adjusted by a vertical screw 64, which extends through the bottom of

the member 62 and through an arcuate slot 65 provided in the plate 39, the lower end of the screw 64 being provided with a nut 66 adapted to bear against the under side of the plate 39.

70 A horizontal transverse plate 67, Figs. 6, 9 and 11, is slidably mounted between projections 68, depending from the frame 1. Extending downwardly from the plate 67 is a bolt 69 on which is rotatably mounted a 75 roller 70, which is adapted for travel in the channel member 62, and which effects reciprocation of the plate 67 when the plate 39 is reciprocated.

80 A swinging frame 71 has its ends embracing and pivotally supported by the tube 3, and is provided with a downwardly extending arm 72 in the lower end of which is supported on a transverse pin 73, a roller 74, which is disposed between two upwardly extending plates 75, secured to the upper side of the plate 67. When the latter plate is oscillated, the frame 71 will be oscillated on the tube 3. Carried by the frame 71, are upwardly extending spring arms 76 and 77, 85 which respectively support two longitudinal guiding plates 78 and 79, see Figs. 6, 9, 12 and 13, which are for the greater portion of their length disposed parallel with each other and with the tube 3, and which diverge at their rear ends. As shown in Figs. 9 and 16, and also in Fig. 10, each holder body 24 has secured to opposite sides thereof two horizontal spring plates 80 and 81. On the rear free end of the plate 80, is 100 mounted a roller 82, which is adapted to engage consecutively with the adjacent plates 57, 78 and 60. On the forward free end of the spring 81 is mounted a roller 83, which is adapted to consecutively engage 105 with the adjacent guide plate 57, and plates 79 and 61. The body 24 is provided with a transverse hole 84, in which the rollers 82 and 83 are located.

110 The plates 78 and 79 may be adjusted toward and from each other by means of set screws 85, Fig. 9, mounted in longitudinal bars 86, Figs. 2 and 9, which are supported by arms 87 which extend upwardly from the frame 71.

115 From the foregoing, it will be understood that as the frame 71 is oscillated, the blade holders will be forced by resilient pressure into the honing and stropping positions against the abrading sides of the rotary 120 wheels 4. After the blades have passed the vertical diametrical axial line, of the wheels 4, the abrading surfaces of the latter will be in contact with the adjacent sides of the blades and the contacting portions of the 125 abrading surfaces will be moving upwardly from the upper edges of the blades, so that there will be no tendency of the latter to dig into the abrading surfaces.

130 From the foregoing, it will be understood

that, when the motor 21 is running, and the lower ends of the blade holders are consecutively inserted in the tube 3, from the rear end thereof, and forward of the pawl 49 in its rearmost position, said pawl will consecutively engage the blade holders and will force them forwardly, until the forward limit of the movement of the member 33 is reached, which will be when the pin 51 lifts the pawl 35 to release the pawl from the block 38, as shown in Fig. 6. After this time, the succeeding blade holders will force the preceding ones forwardly, and when the latter enter between the guide plates 78 and 79, which will be at the time the latter align with the plates 57, as shown in Fig. 13, the blade holders between the plates 78 and 79 will be oscillated so that the blades 27 carried thereby will alternately be brought against the abrading sides of the wheels 4.

When the holders are fed forwardly out of contact with the abrading wheels 4, the holders will pass between and will be supported in an upright position by the guide plates 60 and 61.

If for any reason, the operator should cease feeding either blade holders or slugs into the tube 3, the forward feeding of the blade holders in the machine at the time would cease, and those engaged with the oscillating frame 71 would be subjected to the sharpening operation until forced out of the machine by the insertion of other blade holders or slugs 55, 35 into the feeding end of the tube 3. By lateral adjustment of the guide member 62, the stroke of the frame 71 may be varied, and further adjustment, with relation to the blade holders may be obtained by adjustment of the set screws 85.

By having the base portions 25 of the blade holders formed as shown and described, the blade holders are capable of small lateral movement in any direction, so as to conform to the inequalities of the surfaces of the abrading wheels 4.

The pawl 49 drops by gravity to the engaging position, and in passing rearwardly, it will pass under the blade holder which is 50 in the position at the right as shown in Fig. 6.

I do not limit my invention to the structure shown and described, as many modifications, within the scope of the appended 55 claims, may be made without departing from the spirit of my invention.

What I claim is:

1. In a machine of the kind described, a 60 rotary abrading wheel having a flat abrading side comprising a stropping surface and a honing surface concentric and flush with each other, a plurality of blade holders, a supporting guiding means for said holders, means for feeding said holders along said guiding means, and means by which said

holders are moved to the sharpening position with respect to said side on said guiding means, substantially as set forth.

2. In a machine of the kind described, a 70 rotary abrading wheel having a flat abrading side comprising a stropping surface and a honing surface disposed concentric with each other, a plurality of blade holders, a guiding support for said holders, means for feeding said holders along said guiding means, and means by which said holders are moved to the sharpening position, with respect to said surfaces, on said support, substantially as set forth.

3. In a machine of the kind described, a 80 rotary abrading wheel having a flat abrading side comprising a stropping surface and a honing surface disposed concentric and flush with each other and concentric with the axis of the wheel, and means by which a razor blade may be brought into sharpening relationship to said surfaces consecutively, substantially as set forth.

4. In a machine of the kind described, a 90 rotary abrading wheel having a flat side 90 comprising a stropping surface and a honing surface concentric with each other and with the axis of the wheel, a plurality of blade holders, a guiding support parallel with said surfaces, on which said holders are 95 adapted for travel, means for feeding said holders along said support, and means by which said holders are moved to the sharpening position on said support with relation to said surfaces, after said holders have crossed in their travel a diametrical line through said wheel perpendicular to the line of travel of said holders, substantially as set forth.

5. In a machine of the kind described, moving abrading means, a plurality of blade 105 holders, a guiding support, feeding means by which said holders are fed in successive order along said guiding support arranged to feed each holder along said support to a pre-determined position, after which said 110 holder is fed forwardly on said support by the succeeding holders and by which said holder feeds forwardly the preceding holders, and means by which said holders are moved on said support to the sharpening 115 position with respect to said abrading means, substantially as set forth.

6. In a machine of the kind described, moving abrading means, a plurality of blade 120 holders, a guiding support, feeding means by which said holders are fed along said support in consecutive order and arranged to feed each holder to a pre-determined position, after which said holder is fed forwardly by the succeeding holders and by 125 which said holder feeds forwardly the preceding holders, means by which said holders are moved on said support to the sharpening position with respect to said abrading means, and means by which the feeding means can 130

be operated to feed said holders forwardly from the pre-determined position without the intermediacy of other blade holders, substantially as set forth.

5 7. In a machine of the kind described, a rotary abrading wheel having a flat abrading side, a plurality of blade holders, a guiding support, feeding means by which said holders are fed successively along said support to a pre-determined position and by which the holders are fed forwardly from said position by said feeding means through the intermediacy of a succeeding blade holder mounted on said support and engaged 10 by said feeding means, and means by which said holders are moved on said support to the sharpening position with respect to said abrading side, after the holders have crossed in their travel a diametrical line through 20 said wheel perpendicular to the line of travel of said holders, substantially as set forth.

8. In a machine of the kind described, two abrading means, each having a honing surface and a stropping surface concentric and flush with each other, a plurality of blade holders, a guiding support on which said holders are oscillatable between and into sharpening positions with respect to said 25 two abrading means, means for so oscillating said holders, and means by which said holders are moved consecutively forwardly on said support to said sharpening positions, substantially as set forth.

30 9. In a machine of the kind described, a support, blade holders adapted for travel thereon, means for consecutively feeding said holders along said support to a pre-determined position, means by which each 35 holder on being fed forwardly to said position forces the preceding holders forwardly, and blade sharpening means arranged to co-operate with said holders when the latter are mounted on said support, substantially 40 as set forth.

45 10. In a machine of the kind described, a guiding support, blade holders adapted for travel thereon, means for consecutively feeding said holders along said support to a pre-determined position, means by which each holder on being fed forwardly to said position forces the preceding holders forwardly, blade sharpening means co-operating with said holders when the latter are 50 mounted on said support, and slugs arranged to be fed along said support by said feeding means, when successively mounted on said support, for feeding forwardly the preceding holders when no more holders are 55 mounted in traveling position on said support, substantially as set forth.

60 11. In a machine of the kind described, a guiding support, blade holders adapted for travel along said support in consecutive order one against the other, a frame carrying

said support, blade holder engaging means reciprocative on said frame and having means for consecutively engaging said blade holders, when moved in one direction, and feeding said holders forwardly on said support, a reciprocative member arranged to engage and reciprocate said blade holder engaging means, and means actuated by said reciprocating member for oscillating said blade holders during a portion of their travel along said support, substantially as set forth.

70 12. In a machine of the kind described, two rotary wheels having respectively flat parallel adjacent abrading sides, a guiding support parallel with said two sides, blade holders adapted to be slidably mounted in consecutive order on said support and arranged for lateral oscillation on said support to sharpening positions with respect to said abrading sides respectively, a reciprocative member, and means actuated by said reciprocative member for feeding said blade holders along said support, and means actuated by said reciprocative member for oscillating said blade holders on said support, substantially as set forth.

75 13. In a machine of the kind described, a guiding support, a frame supporting said support, blade holders adapted for travel along said support, blade sharpening means arranged to co-operate with said holders, a member reciprocative on said frame having a pawl arranged to engage and feed forwardly one of said blade holders when the reciprocative member is moved in one direction, a second reciprocative member, means adapted to connect said reciprocative members by which the second member reciprocates the first member, and means actuated 80 when the second member is moving in one direction for operating said connecting means to disconnect said members, substantially as set forth.

85 14. In a machine of the kind described, a guiding support, a frame supporting said support, blade holders adapted for travel along said support, blade sharpening means arranged to co-operate with said holders, a member reciprocative on said frame, two 90 pawls pivoted to said member, one pawl being arranged to engage and feed forwardly one of said blade holders when said member moves in one direction, a second reciprocative member arranged to releasably engage 95 said other pawl so as to reciprocate the first named member, adjustable means by which the last named pawl is detached from said second reciprocative member, when the latter is moving in one direction, and means 100 for reciprocating said second reciprocative member, substantially as set forth.

105 15. In a machine of the kind described, two abrading wheels having parallel adjacent flat abrading sides, a support along 110

which are provided two longitudinal guides, 5 blade holders adapted for travel along said support and held from lateral oscillation thereon by said guides, laterally oscillatable guiding means forward of said guides arranged to swing said holders to sharpening positions with respect to said two abrading sides respectively, and means for laterally oscillating said oscillatable guiding means 10 and for consecutively feeding said holders along said support and consecutively between said longitudinal guides and said guiding means, substantially as set forth.

16. In a machine of the kind described, a 15 channel guide support, a frame supporting the same, a reciprocative member, blade holders adapted for sliding travel in said channel guide support, blade sharpening means arranged to co-operate with said holders, a pawl pivoted to said member and arranged to consecutively engage and feed forwardly said blade holders in said support, and means for reciprocating said member on said frame, substantially as set forth.

25. 17. In a machine of the kind described, a support, blade holders adapted for travel along said support, blade sharpening means arranged to co-operate with said holders, a member reciprocative parallel with said support, means for reciprocating said member, a guiding device carried by said reciprocative member and disposed obliquely to the

line of travel of said member, means actuated by said member for feeding said blade holders consecutively along said support, and laterally oscillatable guiding means adapted to engage and oscillate said holders and engaging and oscillatable by said guiding device, substantially as set forth. 35

18. In a machine of the kind described, a channel guiding support, and a blade holder having one end adapted for travel therein and arranged to swing therein in all directions, and blade sharpening means arranged to co-operate with said holder, substantially 40 as set forth.

19. In a machine of the kind described, a frame, a channel guiding support mounted thereon provided with a longitudinal slot, a blade holder having one end adapted for 45 travel in said support, a member reciprocative on said frame, a pawl pivoted to said member and extending through said slot and adapted to engage said blade holder and to feed the latter forwardly when said member is moved in one direction, and means for reciprocating said member, and blade sharpening means arranged to co-operate with said holder, substantially as 50 set forth.

In testimony whereof I have signed my name to this specification.

VOLNEY T. MILLER.
